UNITED STATES PATENT OFFICE.

WALTER L. SMITH, OF HARTSFIELD, GEORGIA.

PEANUT-HULLER.

1,259,678.

Specification of Letters Patent. Patented Mar. 19, 1918.

Application filed May 28, 1917. Serial No. 171,457.

To all whom it may concern:

Be it known that I, WALTER L. SMITH, a citizen of the United States, residing at Hartsfield, in the county of Colquitt and 5 State of Georgia, have invented a new and useful Peanut-Huller, of which the following is a specification.

The subject of this invention is a peanut huller wherein crusher bars rotate within a 10 cage and are associated with a fan, and the objects of the invention are, first, to provide means for hulling the peanuts and for separately delivering the meat and hulls, second, to provide adjustable means for securing the 15 cage bars, third, to provide a simple and efficient huller.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within 20 in the scope of what is claimed, without departing from the spirit of the invention.

One practical embodiment of the invention is shown in the accompanying drawings, wherein:

30 Figure 1 is a central, vertical, longitudinal section.

Fig. 2 is a side elevation.

Fig. 3 is a plan view with the hopper removed and a portion of the casing broken 35 away.

Referring to the drawings by numerals of reference:—

Front standards 1 and rear standards 2, here shown shorter than the front standards, 40 are provided, and each pair of standards is connected at the bottom by the cross tie piece 3 which is let into the foot of the standards as shown. A base board 4 also connects the lower end of the standards 1 and the standards 2 and extends transversely below the machine body.

Side boards 5 are secured within the standards and rest on the baseboards 4, and the rear ends of the side boards extend 50 beyond the rear standards 2 for a short distance, while the forward ends of these boards are preferably flush with the front faces of the forward standards. A forward top plate 6 and a rearward top plate 7 extend 55 across the machine and rest on the upper edges of the side boards 5, within the stand-

ards 1 and 2. These top plates are spaced apart as shown and may be secured in place in any usual and well known manner. The front of the machine is closed by a bar 8 which extends transversely of the body and is secured to the standards 1 and spaced from the base board 4, and a board 9 which is spaced some distance above the bar 8 and secured to the standards 1. This board 9 and the standards 1 extend for a short distance above the top of the machine.

Extending transversely of the machine within the space between the boards 8 and 9 is a shaft 10 which is journaled in suitable 70 bearings 11 secured to the standards 1. Fan blades 12 are secured to the shaft 10 and the fan is housed in by a semi-cylindrical casing 13 which is detachably secured within the opening between bar 8 and board 9 by pins 75 14 which are secured at each end of the casing 13 and extend into bores formed in the standards 1, and also by hooks 15, pivoted to each end of the casing and adapted to engage an eye 16 secured to each standard 1, 80 or by any other suitable means. The shaft 10 extends beyond its journal at one end and on this end is secured a grooved pulley 17, which is connected by a belt 18 to a pulley 19.

Pulley 19 is secured on one extending end of a horizontally disposed shaft 20 which is journaled in suitable bearings 21 secured to the upper edge of the side boards 5 at a point midway between the opposed edges of 90 the top plates 6 and 7. Arms 22 are secured on and extend radially from the shaft 20 and secured to the free ends of these arms are crushing bars 23. A pulley 24 is secured to the other end of the shaft 20 and may be 95 belted to any suitable source of power.

A substantially arcuate slot 25 is formed in each side board 5 and underlies the shaft 20, and extending transversely of the machine with their ends projecting through 100 these slots, are a series of bars 26 which are held in spaced relation by wedges 27 which are driven between the projecting ends of the bars and lie against the outer face of each side board 5, as shown. As will be apparent a cage is thus formed which lies below and is spaced from the crusher bars 23. The end bars of this cage, as will be seen most clearly in Fig. 1, are restrained not only by the ends of the slots 25, but also by 110 bars 28 which extend transversely of the machine immediately below the opposed edges

of the top plates 6 and 7. The structure just described is housed by a cylindrical casing 29 which is seated on the upper edges of side boards 5 between the plates 6 and 7 and 5 which is detachably secured in place by hooks 30 which are pivotally secured to each side board and engage buttons 31 which are provided on each end of the casing 29, or otherwise. The casing 29 is formed with a longitudinal

10 intake slot 32 for the purpose of admitting peanuts to the cage and crusher bars.

Secured to the side boards 5, and extending transversely of the machine is a board or wall 33 which slopes forwardly and downwardly and partially underlies the cage bars 26. Another board or wall 34 is positioned transversely of the machine, and has its forward edge abutting the front board 9 and top plate 6, from whence it extends rearwardly and downwardly below the cage bars 26, and this wall defines, with the lower edge of the wall 33, a slot 35.

20 A board or wall 36 extends transversely of the machine and has its front edge contacting the front bar 8 from which it extends upwardly and rearwardly and terminates with its rear edge defining, with the rear edge of wall 34, a slot 37. A plate 38 extends transversely of the machine with its 25 front edge projecting through the slot formed between the base board 4 and front bar 8, and this edge underlies a bar 39, which is secured to the lower edge of front bar 8, to form a discharge spout. The plate 38 slopes forwardly and downwardly as seen in Fig. 1.

30 A supporting strip 40 is secured to each side board 5 and a plate 41 is supported on these strips and has a tight sliding fit between the side boards 5. The plate 41 is inclined forwardly and downwardly and its front edge is positioned to aline with the rear edge of the plate 38. As shown in dotted lines, Fig. 1, this plate 41 may be 35 adjusted to leave a slight opening between its forward edge and the rear edge of plate 38.

40 A supporting strip 42 is secured to each side board 5 below the strip 41 and a plate 43 rests on these strips. The plate 43 is arranged on the same incline as the plate 41 and terminates at its forward end below a median line of the plate 41, while its rear edge projects for some distance beyond the 45 rear edge of the plate 41. A transverse wall 44 may extend forwardly and upwardly from the upper edge of the rear base board 4.

Pivotal secured to the upper edge of

the front board 9, as by hinges 45, is a box like hopper 46 which has a transverse slot 60 47 formed at one end of its bottom and adapted to register with the slot 32 when the hopper is in lowered or discharge position. A jointed arm 48 may be pivoted to the side of the machine and the hopper for the purpose of raising the hopper and supporting it in raised position when desired.

50 In practice the device may be placed on top of an open receptacle and, being connected to a suitable source of power, the peanuts fed in to the hopper 46. Peanuts will gravitate from the hopper through the slots 47 and 32 into the cage where the shells will be crushed between the bars 26 and crushing bars 23. The peanuts and shells will drop 55 between the bars 26 onto the plates 33 and 34 from whence they will gravitate through the slot 35. As the meat and hulls leave the plate 34 and drop toward plate 41, they will pass slot 37 through which a blast of air is 60 being directed by the fan. This will blow the hulls and chaff up plate 41 and they will fall from the rear edge of the plate onto plate 43 and gravitate down this plate to the receptacle on which the device stands.

65 The meat, being heavy, will not be affected by the air blast but will gravitate down plate 41 to plate 38 and discharge. As shown in dotted lines, Fig. 1, plate 41 may be moved slightly from contact with plate 38 so that slight particles of chaff or hulls which may have escaped with the meat may drop through the narrow slot thus produced.

70 Having thus described the invention, what is claimed as new is:

75 A peanut huller, comprising a casing, a cage in the casing, crusher bars revolving in the cage, a fan within the casing, means for delivering material to the cage, means for directing material discharged from the cage 80 across the path of air from the fan, an inclined plate below the fan for receiving the heavier material and directing it without the casing said plate being adjustable to discharge small particles therefrom, and an auxiliary plate underlying the first plate and 85 extending rearwardly thereof for receiving the lighter material and directing it toward a given point.

90 In testimony that I claim the foregoing as my own, I have hereto affixed my signature in the presence of two witnesses.

95 WALTER L. SMITH.
